United States Patent

Des. 234,816
Patented Apr. 8, 1975

234,816

GUITAR

Clifford M. Stonerock, Sr., 629 Oak St.,
Dayton, Ohio 45410

Filed June 13, 1973, Ser. No. 369,572

Term of patent 14 years

Int. Cl. D17—03

U.S. Cl. D56—1 A

FIG-1

FIG-2

FIG-3

FIG. 1 is a front perspective view of a guitar showing my new design;

FIG. 2 is a left side elevational view, the right side being a mirror image thereof; and

FIG. 3 is a rear perspective view.

I claim:

The ornamental design for a guitar, substantially as shown and described.
